Filed Dec. 19, 1962, Ser. No. 245,732
5 Claims. (Cl. 4-67)

The present invention relates to toilet flushing mechanisms, and its primary object is to provide a unique new flushing mechanism which is extremely accurate and reliable in operation, and, at the same time, simple and inexpensive to manufacture and install.

In all prior flushing mechanisms, the devices usually work well enough when they are brand new. However, after a period of operation varying from a few months to a few years, the operation of these devices becomes erratic, and malfunctioning begins to occur with increasing frequency. The most common malfunction is failure of the valve ball to seat properly, thereby allowing water to drain out of the tank as fast as it is admitted by the float-controlled refill valve. This highly annoying condition is usually the result of wear in the guide or stem by which the valve ball is guided back down onto the seat; or it may be due to surface roughness caused by corrosion or lime deposits. As the guidance of the valve ball becomes loose and inaccurate, the valve ball tends to hang up, and can only be dislodged by jiggling the handle. This is not only a serious annoyance, but is also expensive, as a great deal of water can be wasted in a relatively short time.

Another common source of trouble in prior flushing mechanisms is the usual linkage connecting the flushing handle to the top end of the stem projecting upwardly from the valve ball. Generally, this linkage consists of a stiff wire or rod depending from the free end of the lift arm attached to the flushing handle, and the bottom end of this wire is bent into a horizontal loop which encircles the stem and slides freely thereon. When the free end of the lift arm is raised, the said loop engages a stop at the top end of the stem, and lifts the stem, thereby unseating the valve ball. The valve ball then rises by its own buoyancy until it reaches a limit stop, where it is held until the receding water level within the tank causes the valve ball to drop back onto its seat. As the valve ball rises and drops in the manner described, the stem slides up and down through the loop in the bottom end of the wire link. Surface roughness of the stem or loop due to corrosion or lime deposits, causes increased frictional resistance to the extent that the stem no longer slides freely through the loop, but instead, hangs up occasionally, and again necessitates jiggling the handle.

With the present invention, these shortcomings of the prior flushing mechanisms are completely eliminated. The valve ball is accurately guided back down onto its seat by a pair of widely spaced guide bearings which are so located, far apart from one another, that the operation of the device is virtually unaffected by wear, corrosion or lime deposits. To obtain maximum spacing between the guide bearings, the said bearings are formed in the outer ends of two supporting arms which are attached to the overflow pipe; the upper arm being attached to the very top end of the overflow pipe, and the lower arm being located only a short distance above the top end of the valve ball. The guide stem projecting upwardly from the valve ball passes through these bearings and is freely slideable therein. In order to accommodate this new guide bearing arrangement, the valve ball stem is extended about twice the usual length for conventional flushing mechanisms, so that the top of the stem stands even higher than the top end of the overflow pipe. The usual linkage connecting the stem to the lifting arm is completely eliminated in the present invention and

2

instead, a wire loop on the end of the lifting arm loosely surrounds the stem above the top guide support arm, and engages the underside of a limit stop knob on the top end of the stem. Both the loop and that portion of the stem engaged thereby are well above the surface of the water at all times, and therefore are not exposed to corrosion or lime deposits. Moreover, there is nothing for the stem to hang up on, nor are there any parts that can become misaligned so that they bind on one another.

One object of the invention is to provide a new and improved float mechanism for the refill valve, which is extremely smooth-acting and reliable in operation, and virtually unaffected by wear, corrosion, or lime deposits.

Another object of the invention is to provide a refill valve float mechanism that is compact, easily installed and serviced, and inexpensive to manufacture.

Still another object is to provide a float mechanism of the class described, in which the float is provided with an enclosed cavity, or chamber, that is partially filled with water which is retained when the float is left hanging in the air by the receding water level as the tank empties.

The foregoing and other objects and advantages of the present invention will become apparent to those skilled in the art upon consideration of the following detailed description of the preferred embodiment thereof, reference being had to the accompanying drawings, wherein:

FIGURE 1 is a sectional view through a toilet tank as seen from the rear, and showing in elevation a flushing mechanism embodying the principles of the invention;

FIGURE 2 is a top plan view of the same;

FIGURE 3 is an enlarged horizontal sectional view, taken at 3-3 in FIGURE 1;

FIGURE 4 is a smaller view, taken at 4-4 in FIGURE 1;

FIGURE 5 is a fragmentary vertical section through the guide means surrounding the valve ball stem;

FIGURE 6 is an enlarged fragmentary sectional view taken at 6-6 in FIGURE 1; and

FIGURE 7 is a vertical sectional view through the float that actuates the refill valve.

In FIGURE 1 of the drawings, the reference numeral 10 indicates a toilet water tank having the usual lid 11. Projecting through holes in the bottom of the tank are a discharge pipe 12 leading to a toilet (not shown) and a water supply pipe 13. A flushing handle 14 on the front of the tank 10 is mounted on one end of a square rod 15, which extends through and is rotatable within a suitable bushing 16 in the front wall of the tank.

The flushing mechanism of the invention is designated in its entirety by the reference numeral 20, and comprises a base member 21 formed integrally with the discharge pipe 12, an overflow pipe 22 which connects into the base member 21 and extends vertically upwardly therefrom, a refill valve 23 controlled by a float 24, and a buoyant valve ball 25. The discharge pipe 12, base member 21, and overflow pipe 22 are preferably made of plastic, although they may be made of brass or other rust-proof material. The base member 21 has an upwardly facing valve seat 30 formed thereon, which receives the valve ball 25. Projecting laterally from one side of the base member 21 below the valve seat 30 is an extension 31 having an internal cavity 32. The bottom end of the overflow pipe 22 is inserted through the top wall of the extension 31 and is rigidly connected thereto; the cavity 32 providing a connecting passageway from the overflow pipe 22 to the discharge pipe 12.

The valve ball 25 is a conventional type in common use at this time, and is usually made of rubber or equivalent material. The valve ball is hollow, providing an airspace

which makes the ball buoyant when submerged in water. Screwed into a bushing (not shown) in the top of the valve ball 25 is a stem 34 which extends upwardly therefrom to a point just above the top end of the overflow pipe 22. The stem 34 is a straight, slender rod of brass or stainless steel, and is preferably of circular cross-section, about one-eighth inch in diameter. Fixed to the top end of this stem 34 and concentric therewith, is a knob 35 having a flat underside.

The stem 34 is supported for vertical sliding movement by two widely spaced guide support arms 36 and 37, which are mounted on the overflow pipe 22 and project laterally therefrom. The upper arm 36 is secured to the overflow pipe 22 at the very top end thereof, and the lower arm 37 is mounted on the overflow pipe a short distance above the top of the valve ball 25. The two arms are identical in configuration, with one minor exception, and the following description therefore applies to both.

The guide support arms 36, 37 are preferably made of plastic, and each is formed with a split collar 40 which surrounds the overflow pipe 22. Projecting laterally from the collar 40 on opposite sides of the split are ears 41, 41' which are apertured to receive a screw 42. The aperture in ear 41 is larger in diameter than the screw 42, so that the latter passes freely therethrough. The aperture in ear 41 is threaded, and the screw 42 is screwed into it, so that when tightened up, the screw clamps the split collar 40 securely onto the overflow pipe.

Projecting laterally from the collar 40 at 90 degrees to the split is the straight portion that constitutes the arm itself, designated 36 or 37, as the case may be, and fixed to the outer ends of the arm are tubular bearings 43, 44. The bearings 43, 44 each has a cylindrical bore through which the stem 34 passes. The bore 45 of the upper bearing 43 is only slightly larger than the diameter of the stem 34, and therefore has only a small amount of clearance to assure free sliding movement of the stem through the bearing. The bore 46 of the lower bearing 44 is considerably larger in diameter than the stem 34, providing additional clearance between the stem and bearing bore so that the stem can shift sideways slightly to accommodate any minor misalignment between the bearings 43, 44 and the valve seat 30. This is best shown in FIGURE 5.

The lower bearing 44 is disposed just a short distance above the top of the valve ball 25 and serves as a limit stop for the latter when the valve ball is lifted clear of its seat and its buoyancy causes it to seek to rise to the surface. The bearing 44 holds the valve ball at that level until the receding water in the tank causes the valve ball to drop back onto its seat.

The stem 34 and valve ball 25 are lifted to discharge the tank by means of an arm 50, which is clamped to the square shaft 15 of the flushing handle. The lift arm 50 has an internally threaded bore provided therein, and a screw-threaded rod 51 is screwed into the bore and locked against turning by a lock nut 52. At its outer end, the rod 51 is formed with a horizontally disposed, elongated loop 53 (best shown in FIGURE 6) which surrounds the stem 34 between the upper bearing 43 and the knob 35. The loop 53 normally rests on top of the upper bearing 43, as shown in FIGURE 1. When the handle 14 is pressed downwardly, the free end of the arm 50 and rod 51 are raised, causing the loop 53 to engage the underside of the knob 35 and lift the stem 34.

The refill valve 23 is mounted at the top end of the overflow pipe 22, and the valve itself is fixed to the top end of a second pipe 54, which lies closely alongside and parallel to the overflow pipe 22. Preferably, the pipe 54 is secured to the pipe 22 by a strap 57, which surrounds both of the pipes. Pipe 54 is actually an outer discharge pipe that is open at the bottom end, and extending upwardly through this outer pipe from the bottom end thereof, is an inner pipe 55, which is connected by a fitting 56

10 to the water supply pipe 13. Thus, water from the water supply pipe 13 is carried to the refill valve 23 through pipe 55, and is discharged by the valve 23 into the tank 10 through the annular space between the inner pipe 55 and the outer pipe 54. Radially inwardly projecting ribs 60 on the inside of the pipe 54 center the inner pipe 55 therein, as shown in FIGURE 3. The valve 23 has the usual overflow pipe or tube 61, which extends down into the top end of the pipe 22, and is secured thereto by a stainless steel clip 59.

15 A pivoted actuating arm 62 projects from one side of the refill valve 23, and hooked into an aperture in the outer end of this arm is a stem 63, which is also in the form of a straight, slender rod of stainless steel or brass. The stem 63 depends from the arm 62, and its lower end passes through and is slidably engaged in a tubular bearing 64 at the outer end of a third guide support arm 65. The arm 65 is identical to the arms 36, 37, and is mounted on the overflow pipe 22 immediately above the lower arm 37.

20 The float 24 is mounted on the stem 63 intermediate the top and bottom ends thereof, and is preferably in the form of a hollow spherical ball made of plastic. The spherical ball float is made up of two virtually identical hemispherical sections 66 and 67 which are cemented together along their mating edges. Projecting inwardly from opposite sides of the ball are tubular sections 70 and 71, which are also cemented together at their abutting ends. The central bore 72 of the tubular sections 70, 71 is tapered slightly from top to bottom, being slightly larger in diameter at the top than at the bottom. The stem 63 passes through the bore 72, and is preferably formed with a plurality of longitudinally spaced enlargements, or lumps, which are formed by pressing indentations 73 into one side of the stem with a stamping tool. The purpose of these lumps, or enlargements, on the stem is to provide a slightly roughened, or irregular, surface for better grip.

25 The float 24 is adjustably secured on the stem 63 by means of a rubber tube, or sleeve 74, which is tightly wedged between the stem and the tapered bore 72. When the float is pulled upwardly on the stem, the sleeve 74 is tightly squeezed between the bore 72 and the stem 63, securely joining them together. However, when the float is pulled downwardly on the stem, the taper of the bore 72 allows the float to be pulled off the sleeve 74, and the latter can then be moved to a new position along the length of the stem 63, if desired.

30 Holes 76 are provided in the sides of the ball float 24 just below the seam 68, and water in the tank 10 enters the ball through these holes and fills the same to the level of the tops of the holes. This water that partially fills the ball is retained therein when the tank is emptied and the ball is left hanging in air by the receding water level, as shown in phantom lines in FIGURE 1. The weight of water contained within the float is sufficient to pull the actuating arm 62 down to the open position, as shown in phantom lines in FIGURE 1. As the tank 10 is refilled, the water level rises about the still-hanging float and increasingly buoys it up until the water level is the same, both inside and out, at which point the downwardly directed force exerted on the float by the weight of the water is zero. When the water level in the tank rises above the water level on the inside of the float 24, the latter becomes buoyant and exerts an upward thrust on the valve arm 62, ultimately moving the latter up to the closed position shown in solid lines in FIGURE 1. As mentioned hereinbefore, this arrangement has the advantage of permitting use of a relatively light weight float of plastic which still has sufficient weight, owing to the load of water that it carries, to pull the arm down to the open position when the tank is emptied. On the other hand, when the tank is refilled, this weight of water is cancelled out by the buoyancy due to the water displaced by the float, and only a small amount of additional

buoyancy is required to close the refill valve 23. No additional buoyancy is required to overcome the dead-weight of solid ballast, as would be the case if the float were loaded with metal weights to give it the necessary mass to pull the arm 62 downwardly.

While I have shown and described in considerable detail what I believe to be the preferred embodiment of my invention, it will be understood by those skilled in the art that various changes may be made in the shape and arrangement of the several parts without departing from the broad scope of the invention as defined in the following claims.

I claim:

1. In a flushing mechanism for use with a toilet tank having a discharge outlet valve seat, a valve ball seating thereon, an overflow pipe, and a water supply pipe, the improvement comprising a refill valve supported on said overflow pipe adjacent the top end thereof, said refill valve being connected to said water supply pipe and having a laterally projecting control lever which is movable vertically between open and closed positions, a stem loosely connected to the outer end of said control lever and depending therefrom, a float attached to said stem intermediate the ends thereof, and a guide arm attached to said overflow pipe and projecting laterally therefrom in the vertical plane of said control lever, said guide arm having bearing means at its outer end slidably engaging said stem below said float.

2. A toilet tank refilling mechanism as set forth in claim 1, wherein said float is provided with an enclosed cavity and has apertures intermediate the top and bottom extremities of the float through which water may pass, said cavity filling partially with water which is retained in the float to give the latter sufficient weight so as to pull said arm downwardly and thereby open said refill valve when the water level within said tank drops below a predetermined level, said weight due to water contained within said float cavity being exactly counterbalanced by the weight of water displaced by said float when the level of water in said tank reaches the level of the water within said float cavity, said float being thereafter buoyed up by the air trapped within said float cavity as the level of the water in the tank rises above the level of the water in the float.

3. A toilet tank refilling mechanism as defined in claim 1, wherein said float is in the form of a hollow spherical ball having a vertical tube running through the center thereof, the interior of said tube being open at both ends, said stem passing through the interior of said tube, and means for frictionally securing said float to said stem, whereby the float can be adjustably positioned along the length of the stem, the wall of said float ball being apertured intermediate the upper and lower extremities of the float ball to permit the latter to fill partially with water, the weight of water contained within the lower portion of said float ball being sufficient to pull said arm downwardly so as to open said refill valve when said tank is emptied, and the buoyancy of the float ball due to air trapped within the upper portion thereof being sufficient to push said valve arm upwardly to shut off said refill valve when the tank is refilled to a predetermined level.

4. A toilet tank refilling mechanism as set forth in claim 3, wherein said stem has a plurality of longitudinally spaced enlargements formed thereon, and said means for functionally securing said float to said stem comprises a sleeve of elastomeric material tightly wedged between said tube and said stem, the interior of said tube being tapered from top to bottom, said sleeve having a tight frictional grip on its outer surface with said tube, and on its inner surface with said stem, said float being easily removed from said sleeve in the downward direction to permit adjustment of the sleeve and float to a new position on said stem.

5. A flushing mechanism for use with a toilet tank having a discharge outlet valve seat, a vertically disposed overflow pipe, and a water supply pipe, said mechanism comprising a buoyant valve ball seating on said valve seat, a rod attached to said ball and projecting upwardly therefrom, a pair of vertically spaced arms attached to said overflow pipe and projecting laterally therefrom, one of said arms being mounted at the top end of said overflow pipe and the other being disposed a short distance above the top of said valve ball, said arms having vertically aligned bearing apertures in their outer ends through which said rod slides freely, the aperture of the top arm being only slightly larger in diameter than said rod, and the aperture of the bottom arm being appreciably larger in diameter than said rod, whereby said top aperture provides a snug sliding fit for said rod, and said bottom aperture provides a loose sliding fit therefore, permitting said valve ball a limited amount of lateral movement as it drops onto said seat, so as to accommodate any misalignment of said valve seat with respect to said bearing apertures, a refill valve supported adjacent the top end of said overflow pipe and connected to said water supply pipe, an actuating lever projecting laterally from said refill valve and movable vertically between open and closed positions, a stem loosely connected to the outer end of said lever and depending therefrom, a hollow float attached to said stem intermediate the ends thereof, said float being partially filled with water which is retained within the float to provide weight sufficient to pull said lever downwardly to the open-valve position when said tank is emptied, the buoyancy of said float due to air space therein being sufficient to push said lever upwardly to the closed-valve position when said tank is refilled to a predetermined level, and another laterally projecting arm fixed to said overflow pipe and having a bearing aperture in its outer end which slidably engages the lower end portion of said stem protruding below said float, so as to guide said float in its vertical travel.
